UNITED STATES PATENT OFFICE.

EDWARD B. SIDES, OF BUFFALO, NEW YORK, ASSIGNOR TO M. H. BIRGE & SONS CO., OF BUFFALO, NEW YORK.

DESIGN FOR EMBOSSED WALL PAPER.

Application filed September 10, 1925. Serial No. 14,748. Term of patent 7 years.

To all whom it may concern:

Be it known that I, EDWARD B. SIDES, a citizen of the United States, residing at Buffalo, in the county of Erie and State of New York, have invented a new, original, and ornamental Design for Embossed Wall Paper, of which the following is a specification, reference being had to the accompanying drawing, forming a part thereof.

The figure shows a face view of a piece of embossed wall paper showing my new design.

I claim:

The ornamental design for embossed wall paper as shown.

EDWARD B. SIDES.
